CHRISTMAS TREE STAND

Alfred J. Schulz, Milwaukee, Wis., assignor to Alfred J. Schulz and Herbert H. Schulz, copartners, doing business under the name and style of S-B Manufacturing Company, Milwaukee, Wis.

Application May 21, 1948, Serial No. 28,503

2 Claims. (Cl. 248—48)

1

This invention relates to Christmas tree stands. The present invention is an improvement over the Christmas tree stand disclosed in United States Patent No. 2,221,205, dated November 12, 1940 and has for its objective the provision of a novel and simplified interlock between the individual legs and the water bowl of the stand.

More specifically, it is the primary purpose of the present invention to provide a Christmas tree stand leg with a hook with which the extreme rim of the water bowl is engaged, the leg being pivotally movable about the point of such engagement to pressure engagement with the water bowl at another point whereby to provide a secure interlock between the parts, the clamping ring engaged with the upper end of the leg being adapted to maintain the interlock between the legs and the bowl.

In the drawings:

Fig. 1 is a view in vertical section through a Christmas tree stand embodying my invention.

Fig. 2 is a fragmentary plan view thereof.

Fig. 3 is a detail view in side elevation of one of the legs.

Fig. 4 is a detail view taken in section on the line 4—4 of Fig. 1.

Fig. 5 is a detail view taken in section on the line 5—5 of Fig. 2.

The Christmas tree stand comprises a bowl 7 provided centrally at its bottom with a tree anchorage stud 8 which may be made from a small piece of triangular stock having its corners 9 turned upwardly and pointed as shown.

As made, the bowl 7 is desirably provided with a relatively broad rim at 10 having a downwardly inclined marginal flange 11. The precise form is not essential, but it is desirable that its shape be such that the legs can individually interact therewith in the manner hereinafter explained, any change in cross sectional design of the rim involving a corresponding change in leg design. At 14 the rim flange is desirably, though not necessarily, embossed to provide leg locating channels at equal angular spacing about the bowl periphery.

The legs 15 are identical. Each is provided at its lower end with a foot at 16 which is preferably substantially horizontal and is desirably embossed to provide a floor-contacting ball 17.

From the foot 16 each leg curves upwardly to 50 a knee portion 18 where the vertical form of the leg changes from concave to convex. From the knee portion 18, the leg extends upwardly at 19 in another concave arc, its upper extremity 20 having a tapped aperture to receive the set 55

2

screw 21 which engages the trunk of a tree supported by the stand. The retaining ring 22 has an overhanging flange at 23 beneath which the upper end 20 of the leg is engaged and firmly retained by the reaction pressure developed by the thrust of the set screw 21 upon the tree trunk. The set screw extends through an aperture at 24 in the retaining ring which positions the leg against substantial lateral displacement but there is no threaded connection between the set screw and the ring, as any such connection would eliminate the reaction thrust which is relied upon to anchor the end of the leg in thrust engagement with flange 23.

The embossed ribs 25, 26, which desirably reinforce the leg, are preferably limited to the concavely arcuate portion thereof at each side of the knee 18. At the knee a hook-shaped tongue 27 is punched from the material of the leg and offset therefrom to be engaged beneath the margin of flange 11 of the bowl. If the rim is channeled as indicated at 14 in Figs. 2 and 5, the sides of the channel will confine the tongue 27 against lateral displacement and the legs can be assembled only at the points where the tongues engage in the channel. At a point remote from the tongue 27, the leg is in thrust bearing contact with the rim 10 as shown at 28 in Fig. 1.

A stand as herein described is readily shipped disassembled and is very easily erected.

To erect the stand, it is only necessary to hook the tongues 27 of the respective legs successively beneath the margin of the rim flange 11 of the bowl (in channels 14, if the rim is channeled). As each such leg is engaged with the bowl, it is pivoted to the upright position in which it is shown in Fig. 1 where the portion of the leg above the hook engages the rim of the bowl, as at 28. The top end of the leg is then connected with the ring 22 by the simple expedient of inserting the flange of the ring over the end of the leg and screwing the set screw 21 through the aperture of the leg into the aperture 24 of the ring.

When interlocking connection is thus effected, the resulting structure is very rigid. The greater the weight imposed thereon, within its capacity, the more securely will the parts interlock with each other. Thus, the weight of a Christmas tree will be imposed in part upon the bowl and in part upon the ring through the respective set screws. The weight imposed upon the bowl is delivered to the hook-shaped tongues 27 of the legs and since these are located inwardly from the feet, the weight will tend to rock each leg inwardly about a fulcrum at its ball 17. This

3

will simply force the leg more tightly in engagement with the rim of the bowl at 28 to resist any such pivotal movement.

Any load imposed on the upper end of the legs through the ring 22 will have a converse action tending to pivot each leg upon the rim at 28 and to thrust each hook 27 outwardly against the rim flange 11, thus firmly interlocking the parts and precluding pivotal movement.

Disassembly of the parts is equally simple, requiring no manipulation other than the mere removal of the set screws and the disengagement of the ends 20 of the respective legs from beneath the overhanging flange of ring 22 whereby each leg may be pivoted outwardly respecting the rim when positioned for complete release, the engagement being merely a hooked engagement.

It is important to the invention that the interlock between the legs of the bowl is not only achieved in simple and inexpensive manner, and is not only very secure mechanically, but is effected without slotting or in any manner perforating the bowl itself. The water-retaining characteristics of the bowl remain unimpaired.

The several prongs of the device 8 for positioning the butt of the tree in the bowl provide a very effective means for that purpose, being adapted to engage butts of different contours more effectively than any single prong could do. The device is easily fabricated and is desirably held to the bowl by a single spot weld or the like.

I claim:

1. In a Christmas tree stand of the type having interlocking legs, ring and bowl, the bowl having a rim of materially larger diameter than the ring and the legs extending divergently from the ring to the bowl and provided with feet at a considerably greater radius than the rim of the bowl, the combination with a bowl having a rim provided with a peripherally continuous flange with a downwardly inclined part, of a leg extending in an outward and downward direction across said rim and flange and having an upwardly inclined hook beneath the leg engaged beneath the downwardly inclined part of the rim flange, said

leg having a rib constituting a fulcrum portion in thrust engagement with the bowl rim at a radius less than that of the flange, said rib being discontinuous between said hook and said fulcrum.

2. In a Christmas tree stand of the type comprising interlocked ring, legs, and bowl, the combination with a bowl having a substantially horizontal and generally circular rim, of a leg having a foot and extending obliquely across said rim and provided at its upper end with ring anchoring means, said leg having concave portions above and below said rim and having an intermediate convex knee portion proximate the rim, said concave portions being provided with medial ribs downwardly offset from the leg portions proper, the leg portion below the knee being provided with a tongue engageable with the rim and the rib of the concave portion of the leg above the knee comprising a seat in thrust bearing engagement with the rim at a point inwardly spaced from the tongue, the ribs being discontinuous through said knee portion and the knee portion being provided with marginal flanges engaging the rim.

ALFRED J. SCHULZ.
